UNITED STATES PATENT OFFICE.

HARRY T. McBRATNEY, OF TARENTUM, PENNSYLVANIA, ASSIGNOR TO VALLEY HOLDING CORPORATION, OF BRACKENRIDGE, PENNSYLVANIA, A CORPORATION OF PENNSYLVANIA.

ANNEALING-BOX.

1,876,448.

Specification of Letters Patent.

Patented May 3, 1921.

Application filed November 4, 1920. Serial No. 421,669.

To all whom it may concern:

Be it known that I, HARRY T. McBRATNEY, of Tarentum, in the county of Allegheny and State of Pennsylvania, have made a new and useful Invention in Annealing-Boxes, of which the following is a specification.

My invention relates to annealing boxes and consists in a sheet metal body adapted 10 to remain rigid under the high temperatures to which such boxes are subjected.

These temperatures are such that no practical construction is rugged enough to have long life. But even for a single use the box 15 must be rigid enough not to collapse. The object of my invention is to provide the requisite rigidity without incurring the expensive construction attendant upon cast-iron boxes or heavy structural boxes, the 20 cost of which is a continuously recurring charge.

Another object is to construct a box which will heat readily and when the heating is completed, will not unduly impede heat 25 radiation from the contents of the box.

These objects are attained by the construction shown in the accompanying drawings in which Figure 1 is a top view of my box; Fig. 2 is a longitudinal vertical section 30 through the box and Fig. 3 is a transverse vertical section through the box.

The box base 1 may be of cast iron, rolled steel or be otherwise formed. It is provided with a continuous trough 2 adjacent 35 its perimeter for sealing purposes. The box sides and ends 3 are of sheet steel having their upper edges flanged at 4 and their adjacent edges welded to provide tight joints. The box top is a rectangular sheet 5 fitting 40 over the flanges 4 and welded thereto. As the lower edges of sides and ends 3 fit in seal trough 2, the box, when assembled, and trough 2 filled with sand or other suitable material, is gas tight.

To prevent collapse of the box top and to facilitate heat absorption and radiation, I apply members 6 of long, rectangular sheets 45 bent longitudinally to V-shape and provided with flanges 7 for welding or riveting to top 50. Members 6 extend the full width of the box and form with top 5 a plurality of box girders which eliminate any tendency of the

top to sag when heated. As members 6 are open at their ends and between their ends, they permit free circulation therethrough 55 of heated gases when the box is in the annealing furnace, and of air when the box is outside of the furnace.

This construction avoids the use of heavy casting or structural reinforcing members 60 with the attending disadvantages and its cost is relatively small so that its scrapping after a number of annealings does not add materially to the cost of the plates being annealed or other product.

Obviously, the side and end walls may be 65 similarly reinforced and variations in the shape of the reinforcing members and other modifications in the box construction may be made without departure from the spirit 70 of my invention.

I claim as my invention:

1. A sheet metal annealing box reinforced by hollow V-shaped stiffeners of sheet metal.

2. In an annealing box, a wall of sheet 75 metal and hollow stiffener members of sheet metal extending across said wall and having open ends.

3. An annealing box comprising a bottom having a perimetric recess, sheet metal side 80 and end walls adapted to seat in said recess and having their adjacent edges welded together, a top supported on said walls and welded thereto, and hollow stiffeners of sheet metal extending transversely of said 85 top and welded thereto.

4. An annealing box top consisting of sheet metal and stiffened with separately formed flanged V-shaped members extending across same with the flanges of said members united to said plate.

5. A sheet metal annealing box reinforced by hollow stiffeners of sheet metal.

6. An annealing box provided with a top plate of sheet metal and stiffener members 95 for same each having an inverted V-shaped cross section with their diverging edges secured to said top plate and open from end to end to provide free circulation of gas or air therethrough.

In testimony whereof, I have hereunto subscribed my name this 2nd day of November, 1920.

HARRY T. McBRATNEY.
